UNITED STATES PATENT OFFICE.

JOHN C. WAHL, OF CHICAGO, ILLINOIS, ASSIGNEE TO REMINGTON ACCOUNTING MACHINE CORPORATION, OF NEW YORK, N. Y., A CORPORATION OF NEW YORK.

CALCULATING MACHINE.

1,418,110.

Specification of Letters Patent. Patented May 30, 1922.

Application filed April 19, 1921. Serial No. 462,621.

To all whom it may concern:

Be it known that I, JOHN C. WAHL, citizen of the United States, and resident of Chicago, in the county of Cook and State of Illinois, have invented certain new and useful Improvements in Calculating Machines, of which the following is a specification.

My invention relates to calculating machines and it is embodied in the present instance in a Remington-Wahl combined type-writing and calculating machine of the character known on the market as a "cross footer", and which machine is disclosed in my Patent #1,270,471, dated June 25, 1918; although it should be understood that the invention is not restricted to its embodiment in such machines.

In the construction disclosed in my said patent certain of the "vertical totalizers" which are carried by and adjustable along the main truck or carriage, are provided with two different sized cams detachably fixed thereto. These cams are adapted during the travel of the carriage to coact with a follower which forms part of the actuator-control, or gear shifting mechanism, for the cross totalizer. When a cam coacts with the follower the movement of the latter actuates the control mechanism to bring about, at the operation of a numeral key, either subtraction in the cross totalizer, or to disconnect and render the latter inoperative, depending on the character or size of the cam.

In accordance with the present invention I provide on each vertical totalizer, or on each of a number of "dummies" which may be substituted for such totalizers if desired, a cam which is adjustably mounted thereon so that it may be set to coact with a follower such as that referred to above, in the same manner as the two different sized cams disclosed in said patent, and also to obtain a setting of each of said adjustable cams for addition. In the construction disclosed in my Patent #1,349,024, dated August 10, 1920, I have embodied two adjustable cams on each vertical totalizer to coact with the control mechanisms of two cross totalizers.

One of the main objects of my present invention is to provide an improved adjustable cam mechanism of the general character specified.

A further object of the invention may be stated in general terms to be to provide sim-

ple, strong and efficient means for affording an adjustment of a cam on and securing it to a carrier, or totalizer, carried by the carriage, whereby said cam may be readily set and effectively and accurately held in any one of several positions to coact with the follower of a totalizer-actuator control mechanism, and in which parts are not apt to become accidentally detached from the machine.

To the above and other ends which will hereinafter appear, my invention consists in the features of construction, arrangements of parts and combinations of devices to be set forth in the following description and more particularly pointed out in the appended claims.

In the accompanying drawings wherein like reference numerals indicate corresponding parts in the various views,

Fig. 1 is a detail fragmentary front view showing a portion of a Remington-Wahl cross footing machine embodying my invention.

Fig. 2 is an enlarged detail front view, with parts broken away, of one of the vertical totalizers shown detached.

Fig. 3 is a side view of the same with parts omitted, and parts in section on line 3-3 of Fig. 2 and looking in the direction of the arrow at said line.

Fig. 4 is a horizontal sectional view of the same taken on the line 4-4 of Fig. 2, and looking in the direction of the arrow at said line.

Fig. 5 is an enlarged detail fragmentary vertical sectional view of the same taken on the line 5-5 of Fig. 2, and looking in the direction of the arrow at said line.

In the drawings I have illustrated only so much of a Remington-Wahl cross footing machine as may be necessary to arrive at an understanding of my invention in its embodiment therein; various of the details of said machine not shown in the accompanying drawings being well known in the art and fully illustrated in my hereinbefore mentioned Patent #1,270,471.

It will be understood that, in the present instance, the follower 1 carried by a crank arm 2 which is mounted on a rock shaft pivoted in the fixed actuator frame 3, may be connected in the usual manner with the actuator-control, or gear shifting mechanism of the cross footer (not shown), as is fully

illustrated in my said Patent #1,270,471. As is well understood, the follower 1 is moved upward by a spring to its highest position where it sets the control mechanism of 5 the cross footer for addition and it can be moved downward under the action of a controlling cam to its lowest position where it sets said control mechanism for subtraction. An intermediate position of said follower 10 under control of a cam results in said control mechanism being set to disconnect the actuator of the cross footer.

The member 4 which is, or may be, of the usual construction, and is sometimes referred to as the "vertical or main truck," is 15 connected to travel with the typewriter carriage. One or more so-called vertical totalizers 5 are detachably mounted on the truck 4, and each is adjustable to different set positions along the truck, where it may be held 20 by a spring-pressed, hand-released, latch 6 adapted to engage teeth 7 on the truck.

The adjustable cam of my invention, which coacts with the follower 1 to automatically position the actuator-control or gear shifting mechanism, in some instances is mounted on each vertical totalizer 5. In other instances it is mounted on each so-called "dummy," which may comprise a 30 frame such as the frame of a totalizer 5 but which contains no totalizer mechanism therein and merely constitutes an adjustable carrier for the adjustable cam, and for other parts, such for example, as the "heel" 8 for 35 the pick-up beam (not shown). Each of these "dummies" is intended to be used in the place of a totalizer 5 when the character of the work is such that no computation is to be entered in a vertical totalizer within 40 the field occupied by the "dummy." With this explanation in mind it will be understood that when I refer herein to a "carrier" for the cam, such term is intended to apply to the support on which the cam is adjust- 45 ably mounted, whether such support be a totalizer 5, a "dummy" or other form of support for the cam.

The frame of a totalizer 5, or of a "dummy," has its side plates 9 apertured at 50 10 to receive and have seated therein lugs or reduced end portions 11 of a vertically disposed supporting or anchorage plate 12, thus fixedly securing said plate to the frame. The front face of this plate 12 is provided 55 with three sets of depressions 13, 14 and 15 arranged at different elevations; one depression of each set being situated near an end of the plate 12. Each of these depressions extends only partly through the plate 12, 60 and is formed with parallel upper and lower side walls 16. A cam plate 17, arranged parallel with the plate 12, has a cam 18 which in the present instance is at the lower edge thereof. This cam plate is made with two 65 rearwardly extending projections 19, each

having parallel upper and lower side walls 20. One of these projections is located near each end of the cam plate in a position to engage in any one of the depressions 13, 14 or 15 at the corresponding end of the plate 70 12, and to fit snugly between the upper and lower side walls 16 of the depression and interlock therewith to prevent any up-and-down movement of the cam plate on the supporting plate 12. Each projection 19 75 may be made by stamping a depression in the front face of the cam plate and crowding the metal at the opposite side of said plate into a die, leaving a strong engaging projection 19 attached at all sides to the 80 plate, and one which at its upper and lower sides fits firmly between and interlocks with the walls 16 of the depression in which it may be seated. The ends 21 of the cam plate 17 are received between and coact with the 85 parallel side plates 9 of the frame, to prevent a longitudinal displacement of the cam plate. The plate 17 has an upright slot 22 therein about midway in the length thereof, the ends of the slot being closed. A threaded spindle, pin or stud 23 passes freely through this slot 22 and is riveted at its rear end, as at 24, to the fixed plate 12. A thumb nut 25 is threaded on the spindle 23 and bears against the front face of the cam plate 95 and forces it rearwardly so as to seat, and maintain seated, the projections 19 in any set of depressions 13, 14 or 15, depending on the up and down position to which the cam plate is adjusted before the thumb nut 100 is tightened. By clamping the plates 17 and 12 together by the thumb nut, the cam plate is accurately located and firmly held in its adjusted position by the interlocking connections between it and the supporting or 105 anchorage plate 12. After backing up the thumb nut on its stud or spindle, the cam plate may be moved forwardly to disengage the projections 19. The cam plate may then be re-adjusted to another position and the 110 projections seated in another set of depressions by adjusting the thumb nut rearwardly. In Fig. 2 the cam plate is shown set in the lowest of its three positions which corresponds to subtraction; and its middle 115 or disconnect position and its highest or addition position, are indicated by broken lines.

It will be understood that the extreme positions of the cam, in a measure, are determined by the closed ends of the slot 22, and that said closed ends also prevent the cam plate from dropping from the machine, or from being disconnected from its carrier when the thumb nut is backed-up and the 125 projections 19 are disengaged from the supporting plate 12.

In order to prevent the thumb nut from being accidentally removed from its spindle I provide means for limiting the backing-up 130

- of the nut. In the present instance such means consist in reducing and threading the forward end portion of the spindle 23, as indicated at 26, to receive a second nut 27 of 5 slightly greater diameter than the main body portion of the spindle. This nut 27 is received in an opening 28 in the outer end of the thumb nut, and is adapted to coact with the bottom wall 29 of said opening to limit 10 the extent to which a thumb nut may be backed-up, and thus prevent it from being accidentally removed from its spindle. In Fig. 2, the nuts 25 and 27 are removed in order better to show other parts.
- 15 In order to aid in effecting the proper adjustment of the cam to any one of the three positions to which it is intended it may be adjusted in the present instance, I have provided indices or symbols "S", "D", "A", arranged successively in the order named on 20 the cam plate and beginning at the top and reading down. These symbols are located adjacent to the slot 22 and each is adapted to be brought substantially into register with 25 the spindle 23 or the thumb nut thereon. This enables the operator to readily determine the point of adjustment of the cam in order to bring about an operation of the control mechanism of the actuator for the 30 cross-foot totalizer for addition, subtraction or "disconnect," accordingly as the symbol "A", "S" or "D" is brought opposite the thumb nut.
- Various changes may be made without departing from my invention.
- 35 What I claim as new and desire to secure by Letters Patent, is,
1. In a calculating machine, the combination of a carriage, a follower forming part 40 of a totalizer-actuator control-mechanism, a carrier adjustable to different positions along the carriage, a plate carried by said carrier and having a cam co-operative with said follower during the travel of the carriage 45 to automatically shift said follower, and means for affording an adjustment of said plate on its carrier to different set positions and for holding it in any of said positions, said means comprising a threaded stud secured to the carrier and passing freely 50 through a slot with closed ends in said cam plate to permit an adjustment of the plate relatively to the stud but to limit the extent of such adjustment and prevent the plate 55 from dropping from the stud and being accidentally detached from the machine, and a thumb screw on said stud to aid in holding the cam plate in its adjusted position.
  2. In a calculating machine, the combination of a carriage, a follower forming part 60 of the totalizer-actuator control-mechanism, a carrier adjustable to different positions along the carriage, a plate carried by said carrier and having a cam co-operative with 65 said follower during the travel of the car-
- riage to automatically shift said follower, and means for affording an adjustment of said plate on its carrier to different set positions and for holding it in any of said positions, said means comprising projections 70 struck up from the body portion of said cam plate and each having parallel upper and lower side walls, an anchorage plate secured to said carrier and provided with sets of depressions at different elevations and 75 which extend only partly through the plate, each depression having parallel upper and lower walls that conform to the corresponding walls on a projection on the cam plate, a threaded stud secured to said anchorage 80 plate and extending freely through a slot with closed ends formed in said cam plate, and a thumb nut on said threaded stud and adapted to bear against the cam plate and hold it in its set position with the projections thereon 85 seated in one or another of the sets of depressions at different elevations in the anchorage plate.
3. In a calculating machine, the combination of a carriage, a carrier carried thereby 90 and adjustable thereon, an anchorage plate secured to said carrier, a plate having a cam thereon, said last mentioned plate being adjustable to three different positions on the anchorage plate, i. e. to an "addition" position, a "subtraction" position, and a "disconnect" position, means which interlock to 95 hold the cam plate to the anchorage plate when the former is clamped against the latter, a threaded stud secured to the anchorage 100 plate and passing freely through a slot with closed ends in said cam plate, a thumb nut on said stud and which bears against the cam plate to clamp it against the anchorage plate, a second nut on said stud to limit 105 the backing or unthreading of the thumb nut and thus prevent an accidental detachment thereof from the carrier, and a follower for a totalizer-actuator control-mechanism with which follower said cam is adapted to coact 110 during the travel of the carriage.
4. In a calculating machine, the combination of a carriage, a carrier carried thereby and adjustable thereon, an anchorage plate secured to said carrier, a plate having a cam 115 thereon, said last mentioned plate being adjustable to three different positions on the anchorage plate, i. e. to an "addition" position, a "subtraction" position, and a "disconnect" position, means which interlock to 120 hold the cam plate to the anchorage plate when the former is clamped against the latter, a threaded stud secured to the anchorage plate and passing freely through a slot with closed ends in said cam plate to permit an 125 adjustment of the plate relatively to the stud but to limit the extent of such adjustment and prevent the plate from dropping from the stud and being accidentally detached from the machine, a thumb nut on 130

said stud and which bears against the cam plate to clamp it against the anchorage plate, a second nut on said stud to limit the backing or unthreading of the thumb nut and 5 thus prevent an accidental detachment thereof from the carrier, and symbols or indices on said cam plate and which are adapted to register with a part on said carrier to indicate whether the cam is set in the "addi-

tion", "subtraction", or "disconnect" position.

Signed at Chicago, in the county of Cook, and State of Illinois, this 15th day of April, A. D. 1921.

JOHN C. WAHL.
